COVER FOR BAKE PANS

Jack Kollman, Chicago, Ill., assignor to Ekco Products Company, Chicago, Ill., a corporation of Illinois

Application September 12, 1952, Serial No. 309,185

5 Claims. (Cl. 220—24)

1

This invention relates to improvements in the construction and assembly of a cover for baking pans and particularly a cover of the type commonly known as a drop cover featuring a reinforcing frame or band adapted to fit around the upper periphery of a pan structure and a metal cover sheet secured to said frame by means of a peripheral flange on the sheet bent downwardly and inwardly about said frame.

A reinforcing frame constructed in accordance with the present invention includes an extension which is bent to lie opposite the face of the frame engaged by the inwardly bent edge of the cover flange whereby said frame presents opposed surfaces between which said edge of the cover flange is gripped to establish a secure and rigid connection between said frame and cover sheet.

It is also an object of this invention to provide a cover and frame assembly of the character described wherein exposed surfaces of the extension and the inwardly bent portion of the cover flange lying outside the area of the extension are arranged in a common plane so as to eliminate any offsets in the surface of the cover facing the sides of the pan set.

In accordance with a preferred embodiment of this invention, notches are formed in the frame to define spaced apart ear-like areas, each of said areas being deformed and elongated to provide a recess in the portion of the frame overlapped by the flange of the cover and to provide an extension which is foldable into a nested position within said recess so as to engage and depress the underlying portion of the cover flange into said recess so that said extension and the portion of the inwardly bent portion of the cover flange lying outside the area of said extension thereby present substantially coplanar surfaces.

With the above and other objects in view, as will be apparent, this invention consists in the construction, combination and arrangement of parts, all as hereinafter more fully described, claimed and illustrated in the accompanying drawings, wherein:

Figure 1 is a top perspective view of a bake pan set (in dotted lines) equipped with a cover in accordance with the present invention.

Figure 2 is an enlarged fragmentary elevational view of a reinforcing frame illustrating the extension as it appears in a state preliminary to deformation and elongation as contemplated by this invention.

Figure 3 is a similar view as the extension appears in a deformed and elongated state.

2

Figure 4 is a vertical section taken on line 4—4 of Figure 3.

Figure 5 is an enlarged fragmentary vertical section showing the cover and frame as they appear with the extension and cover flange in a state prior to final assembly.

Figure 6 is an enlarged fragmentary section on line 6—6 of Figure 1 showing the cover and frame as they appear in final assembled relation.

Figure 7 is an enlarged fragmentary top view of the portion of the cover shown in Figure 6.

Figure 1 of the drawings indicates a multiple baking pan set of three pans secured together within a strapping frame but it will be understood that when desired a fewer or greater number of pans may be included in a set by increasing or decreasing the lengths of the sides of the strapping frame and that a multiple number of pans of various sizes may be accommodated by varying the size of the strapping frame. It is also to be understood that the present invention can be readily used in conjunction with a single pan as well as a pan set having two or more pans.

Referring more particularly to the drawing, each of the pans shown includes a bottom wall 10 of rectangular plan surrounded by upstanding side walls 11. Encircling the walls 11 of each pan and crimped within the flange 12 formed at the upper edges of said walls 11 is a wire 13 which results in the creation of an outstanding reinforcing bead at the upper periphery of each of the pans in the set. The pans are held together by any suitable means such as a strap 14 positioned along and against the exposed walls of the pans. The mounting, and to a large extent, the construction of the straps 14 and the cooperation thereof with the pans, have no particular bearing upon the present invention.

However, in the form of strap 14 shown in the drawings, a reinforcing bead 15 is formed along each longitudinal edge of each strap 14, the upper bead being positioned below the outstanding bead created by the flange 12 and the wire 13 referred to above.

The cover construction contemplated by and forming a preferred embodiment of this invention, includes a reinforcing frame member 16 consisting of a strip of metal bent into a shape adapted to conform with and to loosely embrace the rectangular area defined by the upper edge of the strap 14 positioned along the walls of the pans. A separate top member 17 consisting of a sheet of metal is provided with a peripheral flange 19 which is inwardly folded about the frame mem-

ber 16 so as to position the free edge 20 of such flange 19 inside the frame member 16, as shown in Figure 5 of the drawing. The body of the top member 17 located within the rim portions folded about the frame 16 is preferable arranged in lowered relation to the plane of the rim portions so as to create a bevelled shoulder 21 about said rim portion.

In accordance with the present invention, the frame member 16 includes opposed portions between which the free edge 20 of the flange 19 is gripped. To this end the portion of the frame member 16 overlapped by the free edge 20 of the flange 19 is provided with pairs of notches 22 and 23 arranged at selected intervals along the upper edge of the frame member 16. Each pair of cooperating notches 22 and 23 defines an ear-like area, as shown in Figure 2, which is deformed and elongated to provide an extension 24 as shown in Figures 3 and 4. Such deformation and elongation is accomplished by subjecting the ear-like area to pressure between dies or the like.

Incident to such deformation and elongation, the extension 24 and the portion of the area between said notches which joins the extension 24 to the frame 16 is offset inwardly from the face of the frame 16 overlapped by the free edge 20 of the cover flange 19 whereby the area between said notches and located below the upper limits of the frame 16 provides a recess 25.

The extension 24 is initially bent from an upstanding position, as shown in Figure 5, to an angular position relative to the frame 16, as shown in Figure 6. In such angular position of the extension 24, the flange 19 of the cover top member 17 is adapted to be bent into conformity with the inner contour of the frame 16 so as to position the free edge 20 in overlapping engagement with the inside face of the frame 16 and close to the underside of the extension 24.

After the frame and cover are so assembled, as shown in Figure 6, pressure is applied to the face of the extension 24 to bend the latter toward the free edge 20 so as to lock the edge 20 under said extension. The operation thus performed on the extension 24 is effective to locate the latter within a plane flush with the surface of the cover flange 19 extending therebelow whereby the inside face of the cover defined by such extensions 24 and the flange 19 of the cover overlapping the inside face of the frame 16, presents a continuous wall free of offsets or shoulders which might otherwise hinder easy application or removal of the cover relation to the pan set. Thus the extension 24 acts on the edge portion 20 overlapped thereby to force the latter into the recess 25 formed in the frame 16 opposite the extension 24 to produce an interlocked relationship between the extension 24, the recess, and the edge portion of the cover flange therebetween. The cover is preferably provided with an opening 26 in upward alignment with each extension 24 whereby a suitable tool for bending the extension 24 into overlapping relation to the edge of the cover flange as shown in Figures 6 and 7, may be moved into engagement with the outwardly facing of the extension 24 from a position outwardly of the cover.

While the form and arrangement of the parts as shown in the drawing and as above described are preferred, the invention is not to be limited to such form and arrangement except so far as

the claims may be so limited, it being understood that changes might well be made in the construction without departing from the spirit of the invention.

5. What is claimed is:

1. A baking pan cover comprising a marginal metal frame member, a separate top member consisting of a single sheet of metal having its marginal portions folded inwardly about said frame member with the edge of said marginal portions terminating interiorly of the frame, said latter edge of the marginal portions being overlapped and engaged by an integral portion of said frame member rebent upon itself.

2. A baking pan cover comprising a marginal metal frame, a separate top member consisting of a single sheet of metal having its marginal portions folded inwardly about said frame member with the edge of said marginal portions terminating interiorly of the frame, said latter edge of the marginal portions being overlapped and engaged by an integral extension of said frame member rebent upon itself.

3. A baking pan cover comprising a marginal metal frame member, a separate top member consisting of a single sheet of metal having its marginal portions folded inwardly about said frame member with the edge of said marginal portions terminating interiorly of the frame, said latter edge of the marginal portions being overlapped and engaged by an integral extension of said frame member rebent upon itself and positioned within a plane defined by the interiorly facing surface of the marginal portions of the cover lying outside the area underlying the extension.

4. A baking pan cover comprising a marginal metal frame member having an angularly bent extension projecting inwardly from one edge thereof, a separate top member consisting of a single sheet of metal having its marginal portions folded inwardly about said frame member with the edge of said marginal portion terminating interiorly of the frame in proximity to the corner defined by the inner face of the frame and said angular extension, said extension being further bent to overlap and have interlocking relation with the aforesaid edge of the marginal portion.

5. A baking pan cover comprising a marginal metal frame member having an angularly bent extension projecting inwardly from one edge thereof, a separate top member consisting of a single sheet of metal having its marginal portions folded inwardly about said frame member with the edge of said marginal portion terminating interiorly of the frame in proximity to the corner defined by the inner face of the frame and said angular extension, said extension being further bent to overlap and have interlocking relation with the aforesaid edge of the marginal portion and a recess in the inner face of the frame opposite said extension and the area of the marginal portion of the cover overlapped by said extension, in which said extension and the marginal portion of the cover overlapped by said extension are confined within a plane defined by the inwardly facing surface of the marginal portion of the cover lying outside the area overlapped by the extension.
